UNITED STATES PATENT OFFICE.

EDWARD C. PREVEAR, OF LEOMINSTER, MASSACHUSETTS, ASSIGNOR TO LEOMINSTER
BUTTON COMPANY, OF LEOMINSTER, MASSACHUSETTS, A CORPORATION OF NEW YORK.

DESIGN FOR A BANDEAU.

40,759.

Specification for Design.

Patented July 12, 1910.

Application filed May 18, 1910. Serial No. 562,099. Term of patent 7 years.

To all whom it may concern:

Be it known that I, EDWARD C. PREVEAR, a citizen of the United States, and resident of Leominster, in the county of Worcester and State of Massachusetts, have invented a new, original, and ornamental Design for a Bandeau, of which the following is a specification, reference being had to the accompanying drawing, forming a part thereof.

The figure is a perspective view of a bandeau, showing my new design.

I claim:

The ornamental design for a bandeau, as shown.

EDWARD C. PREVEAR.
